E. R. METHUDY

GAS RANGE

Filed June 11, 1927

Inventor:
Eugene R. Methudy,
22 Poplar, Kingsland,
His Attorneys.

UNITED STATES PATENT OFFICE.

EUGENE R. METHUDY, OF ST. LOUIS, MISSOURI.

DESIGN FOR A GAS RANGE.

Application filed June 11, 1927. Serial No. 22,407. Term of patent 14 years.

To all whom it may concern:

Be it known that I, EUGENE R. METHUDY, a citizen of the United States, residing in the city of St. Louis and State of Missouri, have invented a new, original, and ornamental Design for a Gas Range, substantially as shown in the accompanying drawing.

The figure is a perspective view of a gas range showing my new design.

I claim:

The ornamental design for a gas range, substantially as shown.

EUGENE R. METHUDY.

CERTIFICATE OF CORRECTION.

Design Patent No. 73,708.

Granted October 25, 1927, to

EUGENE R. METHUDY.

It is hereby certified that the above numbered patent was erroneously issued to the inventor said "Methudy", whereas said Design Patent should have been issued to "Alvin D. Goldman", of St. Louis, Missouri, as assignee of the entire interest in said invention, as shown by the records of assignments in this office; and that the said Letters Patent should be read with this correction therein that the same may conform to the record of the case in the Patent Office.

Signed and sealed this 22nd day of November, A. D. 1927.

Seal.
